TIRE

Mervin Shughart, Carlisle, Pa., assignor to Carlisle Tire & Rubber, Division of Carlisle Corporation

Filed June 26, 1972, Ser. No. 266,380

Term of patent 14 years

Int. Cl. D12—15

U.S. Cl. D90—20 R

FIG. 1.

FIG. 2.

FIG. 1 is a perspective view illustrating my new design for a tire, it being understood that the tread pattern continues as shown throughout the circumference of the tire.

FIG. 2 is an enlarged partial front elevation of the tire's tread.

I claim:

The ornamental design for a tire, as shown and described.
